UNITED STATES PATENT OFFICE.

WESLEY E. LAIRD, OF PITTSFIELD, MASSACHUSETTS, ASSIGNOR TO GENERAL ELECTRIC COMPANY, A CORPORATION OF NEW YORK.

TIME RECORDER.

Application filed May 6, 1926. Serial No. 107,260.

My invention relates to time recorders, and more particularly to time recorders adapted for use in factories and offices for the recording by employees of the times at which they start and stop work. Such time recorders provided with printing mechanism controlled by suitable clockwork are used extensively, each employee usually being provided with a record card which he may insert in the device and on which the various times are stamped by the printing mechanism which is operated by the employee by means of a handle or lever. These record cards have spaces in which the various times are printed by the printing mechanism, the spaces being arranged usually in horizontal lines or rows for the different days of the week and in vertical lines or columns for the times at which work is started and stopped in the forenoon, afternoon and evening. The working hours of different employees are often not the same and frequently even overlap and employees often start or stop work either considerably before or considerably after the regular appointed times. A second handle or lever is therefore usually provided by means of which an employee may so control the mechanism as to cause it to print the time in the proper vertical row or column. The employee thus has the opportunity of selecting each time at will the proper column in which to print on his card the time at which he starts or stops work. It has been found that this permits a dishonest employee to use the device dishonestly and to produce a card printed so as not to indicate truthfully the times at which he actually started or stopped work. Assume, as an example, that the employee knows in the morning that he will be expected to work until ten o'clock in the evening. He may take his card to the recorder at ten o'clock in the forenoon and print that time in the evening "out" column. He may then leave work at any earlier time during the evening and receive credit for full time up to ten o'clock. Many time recorders automatically print a small mark under the figures indicating afternoon or evening time and omit this mark under figures indicating forenoon time, but a dishonest employee may easily add such a mark with a pencil or erase the mark if it has been printed and is not desired. As another example of dishonest use of the re-

corder, suppose an employee is expected to start work at eight o'clock in the forenoon. He may arrive at his work late but may know that he will work until eight o'clock or later in the evening. He may then purposely fail to print his card in the morning, but may take his card to the recorder at eight o'clock in the evening and print that time in the morning "in" column and receive credit for full morning time from eight o'clock. The general object of the invention is to provide a time recorder with means which will restrict an employee's selection or control of the spaces in which his card is printed, but which will at the same time permit such selection or control as is necessary because of the different and overlapping working periods of different employees.

The invention will be better understood from the following description taken in connection with the accompanying drawing in which Fig. 1 shows one form of the invention applied to so much of the printing mechanism of a time recorder as is necessary for a clear understanding of the invention; Figs. 2 and 3 are detail views of a portion of the device, and Fig. 4 shows a record card such as may be used in connection with the time recorder.

Like reference characters indicate similar parts in the different figures of the drawing.

The invention is shown in the drawing in a form which is particularly applicable in connection with an arrangement of time recorder printing mechanism which is already extensively used and which comprises a type wheel 10, a record card holder 11 and a hammer 12. A record card 13, such as is shown in Fig. 4, may be inserted in the card holder 11 with the face of the card at the back and toward the type wheel 10 with a suitable carbon ribbon 14 between the card and type wheel. The type wheel 10 is driven by suitable clockwork to keep the proper type indicating the correct time always under the hammer 12 so that a stroke of the hammer will always cause the correct time to be printed on a card properly placed in the holder. The card holder 11 rests loosely on a supporting rod 15 and its upper portion is in sliding engagement with a guide rod 16 so that the holder may slide freely to carry any selected vertical column of a record card between the type wheel 10 and the hammer 12. The position of the card holder and

record card may be adjusted horizontally by means of a handle 17 which projects from the card holder through a slotted plate 18 adapted to be secured over an opening in the front of a suitable casing enclosing the printing mechanism. The plate is provided with notches and indicating marks so that this adjustment of the position of the card holder and card may be made accurately. In order that the time may be printed in the proper horizontal row or line of spaces on the record card, some suitable adjustable stop is usually provided to determine the depth to which the card may be inserted in the card holder but this feature is not shown as it forms no part of the present invention.

The mechanism so far described would permit the time to be printed in any selected column of the record card at any time and opportunity would thus be afforded for its dishonest use as has already been explained. In accordance with the invention, means is provided to restrict this freedom in the selection of the space in which the printing of the time will appear on the record card. A locking or stop member 19 is mounted on a supporting rod 20 about which it may tip or rotate into various desired positions. This locking member 19 is engaged by an arm 21 of a control member 22 supported on a rod 23. The member 22 has a second arm 24 with a pin 25, which rides against a cam 26, having three sections 27, 28 and 29 and being fixed to a shaft driven by clockwork to turn once in twenty-four hours. The locking member 19 has a heavy rear extension 30 which tends to tip or rotate the locking member to the rear and by pressure on the control arm 21 to hold the pin 25 against the cam 26. The cam 26, control member 22 and extension 30 of the locking member 19 thus constitute automatically controlled means for determining the position of the locking member.

45 The cam 26 is shown in Fig. 1 of the drawing with its lower or inner section 27 against the pin 25 so that the locking member 19 is tipped backward. In this position of the locking member 19, a stop 31 projecting therefrom is located close to the rod 15 and in the path of the base of the record card holder 11, thus locking the card holder 11 to the left of the stop and in such relation to the type wheel 10 that the time may be printed in the morning spaces but not in the evening spaces of a record card. The section 27 of the cam is so arranged that this condition is maintained throughout at least those hours of the morning and forenoon during which the time might otherwise be printed dishonestly to give a false record in an evening space. It is thus impossible at any time during the forenoon for the time to be printed in an evening space on the record card and thus produce a false record. The

first one to use the recorder in the morning may, or course, find the card holder at the right in an afternoon or evening position where it was last used on the previous day. If so, a projecting plate 32 on the base of the card holder 11 will hold the stop 31 out of its locking position and the card holder will slide freely to the left into its morning position. This will move the plate 32 beyond the stop 31, which will immediately move to its locking position and prevent a return of the card holder to an afternoon or evening position.

Assuming that no work will be done after ten or eleven o'clock in the evening, then by noon or thereabouts it will be too late for an employee to print a time dishonestly in the evening spaces on his record card and through the early part of the afternoon there will be no opportunity for dishonest use of the recorder. Near noon, therefore, or shortly before the first employees return to start their afternoon period of work, the rotation of the cam 26 will bring its intermediate section 28 onto the pin 25 and thus move the control member 22 and its arm 21 to tip forward the locking member 19 into an intermediate position as shown in Fig. 2 of the drawing. In this position of the locking member 19, its stop 31 is just out of the path of the card holder 11, which is therefore free to slide on its support and may be moved by the handle 17 into any desired position. There is sufficient elasticity in the arm 21 and other parts to permit the stop 31 to be held out of its locking position by the plate 32 without breaking or permanently distorting any of the parts. The recorder may now be used both by employees leaving their morning period of work and by those returning to start their afternoon period, even though these periods may overlap.

At some suitable time during the afternoon and after all employees should have left their morning periods of work, the outer section 29 of the cam 26 reaches the pin 25 and acts through the control member 22 and its arm 21 to tip the locking member 19 into its forward position as indicated in Fig. 3. In this position of the locking member 19, a stop 33 carried thereby is brought into the path of the card holder 11 to lock it out of the morning position. The recorder is still free to be used to print the time in the proper spaces throughout the remainder of the afternoon and evening, but it is now impossible to print any dishonest time in the morning space. The back of the stop 33 is beveled so that if the card holder 11 happens to be in its morning position when the locking member 19 and its stop 33 are tipped forward, the card holder may be moved past the stop to its afternoon or evening position. As this is done, the elasticity of the parts permits the stop 33 to yield but the stop

moves forward into its locking position again as soon as the card holder has passed beyond it, the card holder then being locked out of the morning position.

5. The application of the invention to a time recorder does not interfere in any way with the proper use of the recorder at any time but it prevents such improper recording of time as to indicate that the record was made 10 at a certain time when it was actually made at some other time. One form of the invention has been described in detail as applied in a particular way to a well known and commonly used type of time recorder, but various 15 modifications may of course be made within the scope of the invention as defined in the appended claims.

What I claim as new and desire to secure by Letters Patent of the United States is:—
20 1. A time recorder including a card holder, means for printing time records in a plurality of spaces on a card in said holder, manually controlled means for moving said card holder to select the space in which each 25 time record is printed, and automatic means for restricting the manually controlled movement of said card holder.

2. A time recorder including a card holder, means for printing time records in a plurality of spaces on a card in said holder, manually controlled means for moving said card holder to select the space in which each time record is printed, and automatic means for alternately preventing and permitting 35 the manual movement of said card holder to certain record receiving positions.

3. A time recorder including a card holder, means for printing time records in a plu-

rality of spaces on a card in said holder, manually controlled means for moving said 40 card holder to select the space in which each time record is printed, and automatic means for preventing the manual movement of said card holder to certain record receiving positions only during one period of time and 45 to other record receiving positions only during another period of time.

4. A time recorder including a card holder, means for printing time records in a plurality of spaces on a card in said holder, 50 manually controlled means for moving said card holder to select the space in which each time record is printed, and automatic means for preventing the manual movement of said card holder to certain record receiving positions only during one period of time and to certain other record receiving positions only during another period of time, said automatic means being further arranged to release said manually controlled means to permit 55 free movement of said card holder to any record receiving position during a third period of time.

5. A time recorder including a card holder, means controlled by clockwork for printing time records in a plurality of spaces on a card in said holder, manually controlled means for moving said card holder to select the space in which each time record is printed, and means automatically controlled by 60 said clockwork for restricting the manually controlled movement of said card holder.

In witness whereof, I have hereunto set my hand this fourth day of May 1926.

WESLEY E. LAIRD.
